COMBINED CABANA AND SOLARIUM THEREFOR

Mike Tecton, Oklahoma City, Okla.
(5101 45th St. NW, Washington, D.C.)

Filed Jan. 6, 1965, Ser. No. 83,309

Term of patent 14 years

(Cl. D83—1)

FIGURE 1 is a front perspective view of a combined cabana and solarium therefor embodying my new design;

FIGURE 2 is a top plan view thereof;

FIGURE 3 is a rear elevational view thereof;

FIGURE 4 is a side elevational view thereof.

I claim:

The ornamental design for a combined cabana and solarium therefor, as shown.
